US00D587334S

(12) **United States Design Patent**
Cink

(10) **Patent No.:** **US D587,334 S**
(45) **Date of Patent:** **** Feb. 24, 2009**

(54) **TERMITES STATION CONTAINER**

(75) Inventor: **James H. Cink**, Ballwin, MO (US)

(73) Assignee: **Whitmire Micro-Gen Research Laboratories, Inc.**, St. Louis, MO (US)

(**) Term: **14 Years**

(21) Appl. No.: **29/281,688**

(22) Filed: **Jun. 28, 2007**

(51) LOC (9) Cl. **22-06**

(52) U.S. Cl. **D22/122**

(58) Field of Classification Search D22/119-124;
43/1, 58, 60, 107, 121, 131, 132.1, 124, 112-113;
248/530, 156, 545

See application file for complete search history.
